INVENTOR:

G. L. McKNIGHT

United States Patent Office.

G. L. McKNIGHT, OF WORCESTER, MASSACHUSETTS

Letters Patent No. 65,253, dated May 28, 1867.

IMPROVEMENT IN CALIPERS.

The Schedule referred to in these Letters Patent and making part of the same.

KNOW ALL MEN BY THESE PRESENTS:

That I, G. L. McKNIGHT, of the city and county of Worcester, and Commonwealth of Massachusetts, have invented certain new and useful Improvements in Calipers, Dividers, and Draughting Instruments; and I do hereby declare that the following is a full, clear, and exact description of the same, reference being had to the accompanying drawings forming a part of this specification, in which—

Figure 1 represents a side view of so much of a caliper or other similar instrument as is necessary to illustrate my invention.

Figure 2 represents a vertical central section on line A B, fig. 1.

Figure 3 represents a cross-section on line C D, same figure; and

Figure 4 represents a side view of one arm of a caliper.

In the drawings the part marked A represents the body of the instrument, in which are slots *a a* to receive the upper ends of the forks, arms, or legs of the instrument, which are pivoted to the body at the points *b b*. From the upper part of A rises the standard B, upon which is cut a thread, *c*, to fit the screw-thread *d* in the nut C. The upper end of the standard *d* is bored out, and is so provided with slits *e e*; one or more may be used. A screw, D, is fitted to work into the top of the standard B, as clearly indicated in the drawings. E is a spring which passes through a hole in the top of the part A, and as the hole is a little smaller in diameter than the width of the spring E, the latter when driven in is retained in a very secure position. The ends *ff* of the spring are bent down into the slots *a a* before the arms or forks of the calipers or other instruments are hinged or pivoted to the part A, so that the ends *ff*, of spring E, acting upon the arms or forks of the instrument, cause them to expand until their upper ends, which are to be made in the form shown in fig. 4, strike against the nut C, which can be screwed up or down upon the standard B, to adjust the lower ends of the arms of the calipers or other instrument to the desired distance apart, when, by turning screw D down, the slotted end of standard B is expanded, thereby binding nut C securely in the desired position to hold the arms, forks, or legs of the instrument in the proper position for use.

It will be seen that after the instrument is once adjusted for use, which can be readily done, there is no danger of displacement of the parts either by handling, dropping, or otherwise.

My invention is designed to obviate the use of the expensive spring-top caliper, divider, and similar instruments. As applied to calipers it answers equally well for those used for caliperizing inside as well as outside surfaces. In lieu of a flat spring, E, a small spiral spring may be placed in the hole *g*, to force the arms or forks apart.

Having described my improvements in calipers and other similar instruments, what I claim as new, and of my invention, and desire to secure by Letters Patent, is—

1. The combination, with the slotted standard or screw B, of the screw D, for holding the adjusting-nut C, substantially as described.
2. The combination, with the upper part of the body or part A, of the spring E, substantially as and for the purposes set forth.

G. L. McKNIGHT.
